(57) **CLAIM**

The ornamental design for an antenna, as shown and described.

DESCRIPTION

FIG. 1 is a front perspective view of the antenna, showing my new design;

FIG. 2 is a back perspective view thereof;

FIG. 3 is a front elevation view thereof;

FIG. 4 is a back elevation thereof;

FIG. 5 is a bottom plan view thereof;

FIG. 6 is a top plan view thereof;

FIG. 7 is a right elevation view thereof;

FIG. 8 is a left elevation view thereof; and

FIG. 9 is a perspective view thereof in use with a base;

FIG. 10 is a perspective view thereof in use on furniture;

FIG. 11 is another perspective view thereof in use with a base;

FIG. 12 is a perspective view thereof in use on a wall;

FIG. 13 is still another perspective view thereof in use with a base; and,

FIG. 14 is another perspective view thereof in use on a wall. The broken lines in the figures show areas of the antenna and also environment which form no part of the claimed design.
